MEANS FOR TYING BOTTLES TOGETHER
FOR STACKING PURPOSES, SUCH AS IN
DISPLAYSAnson A. Merrick, Detroit, Mich., assignor to
James Vernor Company, Detroit, Mich.

Application July 28, 1936, Serial No. 93,094

3 Claims. (Cl. 211—74)

In the preparation and arrangement of window displays featuring bottled goods, or bottles, it is often desired to stack them in forms which are novel and which will attract attention, such 5 as in the shape of pyramids. This has been accomplished in the past to some extent by the arrangement of a layer of standing bottles upon which is placed a sheet of glass, then placing an additional tier of standing bottles thereon, then 10 another sheet of glass, and by thus repeating the process until the desired type of display has been constructed.

This process has not been entirely satisfactory because of the necessity for using glass, which 15 is frequently broken, and there is also the hazard of some of the supporting bottles slipping and allowing the whole structure to fall, with possible injury to persons who are nearby as well as property loss resulting from the breaking or bursting of the bottles.

There appears to have been no substantial advance in the art involved in this method or means for arranging such displays, and consequently there has been resulting loss of attraction and 20 advertising value, which further emphasizes the necessity for a new means and method for making displays such as that provided for by my invention.

The general purpose of my invention, therefore, is to provide a new and useful means and method for stacking bottles for display purposes, which will attract attention because of its novelty and provide for sturdy construction.

A further object of my invention is to provide 35 for the stacking of bottles for display purposes without the use of glass sheets upon which to rest the bottles.

Another object of my invention is to eliminate the hazard of personal injury and destruction of 40 the display by providing means whereby the bottles will not slip or fall.

Another object of my invention is to provide a means for stacking bottles in such manner as to utilize to the best advantage the available 45 space for the display whether it be small, large, circular, rectangular, or of irregular shape.

Other objects of my invention are the providing of uniform means for making small or large displays, to provide a means which is economical 50 in cost and easily transported, and one which can be seen only upon close examination of the display and which therefore contributes greatly to arouse the curiosity and attract attention.

I attain these objects by the means and method 55 shown in the accompanying drawing, in which—

Figure 1 is an elevational view of the stack of bottles in which the supported bottle is in upright position, and showing the stack tying means comprised in my invention.

Figure 2 is an elevational view of a stack of bottles showing use of my invention, but in which the supported bottle is in inverted position. The stack tying means shown in Figures 1 and 2 is shown with enlarged diameter, or thickness, for 5 purposes of illustration.

Figure 3 is a sectional view of the stack of bottles and stack tying means on line 3—3 of Figure 1.

Figure 4 is a sectional view of the stack of bottles and stack tying means on line 4—4 of Figure 1.

Figure 5 is a sectional view of the stack of bottles and stack tying means on line 5—5 of Figure 2.

Figure 6 is a top plan view of the bottle stack 20 tying means shown in side elevation below line 3—3 in Figure 1 and below line 5—5 in Figure 2. Label or tag means secured to the tying means is also shown.

Figure 7 is a sectional view of the bottle stack 25 tying means on line 7—7 of Figure 6, and shows the label or tag means affixed to the stack tying means.

Figure 8 is a top plan view of the bottle stack 30 tying means shown in side elevation below the line 4—4 in Figure 1.

Figure 9 is a sectional view of the bottle stack 35 tying means on line 9—9 of Figure 8.

Figure 10 is a schematic view in elevation of a stack of bottles showing the use of my invention 35 and including a combination of either a plurality of groups such as that shown in Figure 1, a plurality of groups such as that illustrated in Figure 2, or a combination of the two types of groups illustrated in Figures 1 and 2. The stack tying 40 means is shown in enlarged diameter or thickness to better illustrate the details of its use and construction.

Figure 11 is a sectional view of the loop members such as those comprised in the stack tying 45 means illustrated in Figure 8, with the body of the loop split for use double in the manner illustrated in Figure 10.

Figure 12 is a sectional view on line 12—12 of Figure 11, showing the configuration of the split 50 loop in enlarged form.

Figure 13 is a section of the loop members such as are comprised in the stack tying means illustrated in Figure 6, with the loop split for use double in the manner illustrated in Figure 10. 55

Figure 14 is a sectional view on line 14-14 of Figure 13 showing the configuration of the split loop in enlarged form.

Figures 15, 16, 17, and 18 are top plan views 5 of the stack tying means comprising my invention, in varying forms.

One of the primary purposes of the stacks shown in Figures 1 and 2 is to provide a solid foundation for a pyramiding arrangement in 10 the display. This is accomplished by arrangement of the pyramid with the stack illustrated in Figure 1 or Figure 2 as a unit. Thus instead of each bottle in the foundation of the pyramid being a separate unit, a plurality of bottles are 15 combined and tied together as a unit, which greatly increases the strength of the foundation and eliminates the hazard of overturning or slipping such as would exist if the bottles were used separately.

20 In further explanation of my invention, and referring to Figures 1, 3, and 4, the three bottles A, B, C, forming the foundation of the stack are arranged in the position shown, and the base tie member 1 shown in Figure 8, which is of wire or 25 other substantially rigid material, is so formed that the loops conform to the curvature of the bottle wall in order that the base of each bottle may be inserted within a loop. The wire or other material of which the tie is made must be 30 of sufficient strength to hold the bottles in position once they are placed therein and without likelihood of spreading at the base of the stack.

The top tie member 2 illustrated in Figure 6 is then placed in position over the tops and 35 around the bottles near the base of the necks or on the shoulders thereof. The top tie member is also formed of wire or other substantially rigid material, and is similar in shape to the base tie member excepting that the loops are of 40 smaller diameter and the intervening reverse curves extend further toward the axial point thereof.

The diameter of the loops of the top tie member 2 is governed by the diameter of the bottle neck 45 or shoulder at the point on which the loop is to rest, which is the same whether the supported bottle is in upright position as shown in Figure 1 (bottle D) or in inverted position as shown in Figure 2 (bottle E). This is for the reason that 50 the diameter of the inverted bottle E at the point it rests upon the shoulders of the supporting bottles A, B, C, is substantially the same as the diameter of the upright supported bottle D at its point of contact with the supporting bottles. 55 The loops of the top tie member 2 are accordingly in the same plane in both Figure 1 and Figure 2. In neither type of stack, however, does the weight of the supported bottle (D or E) rest upon the tie member. It rests upon the shoulder 60 of each of the three supporting bottles A, B, C, forming the foundation of the stack.

This is explained by referring to Figure 1, where one-third of the weight of the supported bottle D acts on point a of the lower bottle C, 65 but in a direction normal to the curve of the shoulder of the lower bottle C at a, or ac. Resolving this into vertical and horizontal components there is a vertical force equal to one-third of the weight of the bottle acting downward on the line ad, and a horizontal component ab which equals ad times cotangent bac.

This horizontal component would cause the supporting bottles A, B, C, to slide were it not 70 for the friction between the base of the table,

or support. This is further prevented by use of the base tie member 1 shown in Figure 8.

The friction and the force ab form a couple which causes the bottle C to topple over outward from the upper bottle D. If the horizontal component ab is balanced by an equal and opposite force the arrangement becomes stable since the vertical component is balanced by the resistance exerted by the supporting table. A tie 2 such as that illustrated in Figure 6 around the supporting bottles A, B, C, at the horizontal plane which includes the points a and b will balance the forces tending to topple the supporting bottles and will make a stable arrangement providing the tie member is held in that plane. 15

The tendency for any such tie is to slip upwardly along the shoulders and neck of the supporting bottles. This is prevented by providing that the axial distance between each of the reverse curves intervening the loops is slightly less than the outside diameter of the supported bottle (D or E) at the point where it rests upon the supporting bottles. In this way such reverse curves of the tie 2 are impinged against the bottle surface, whether it be the side wall of the inverted 25 bottle E or the base of the upright bottle D, at a point just below its point of contact with the supporting bottles. This prevents any upward movement of the tie 2 and keeps it in substantially the same plane as such points of contact 30 between the supporting and supported bottles.

The tie 2 shown in Figure 6 may, of course, be varied in form so long as the essential features previously pointed out are retained. For example, particularly for use in stacks such as that 35 shown in Figure 1, the tie means shown in Figures 15, 16, 17, and 18, provide the means for balancing the forces tending to slide or topple the supporting bottles and preventing upward slipping of the tie. Tie means such as those shown 40 in Figures 15, 16, 17, and 18 also provide the additional advantage that, because they comprise only straight lines connecting their points of contact with the bottles A, B, C, on which the outward pressure is being exerted, they may be 45 made of flexible material (such as cord).

Figure 10 illustrates some of the various ways of combining the stacks illustrated in Figures 1 and 2. The diameter or thickness of the tie members 1, 2 is shown enlarged for the purpose of 50 illustrating details.

Describing the arrangement from the left hand side, there is first shown the combination shown in Figure 1, with the base bottle B in the rear of the stack. 55

The second stack of the same design is then combined with the first by using in common with its two supporting bottles B, C, the right hand bottle C of the first stack, which thus becomes bottle A in the second group. 60

A stack of the same design as that shown in Figure 2 with base bottle B in the rear of the stack is then shown, likewise combined with a stack similar to that shown in Figure 1 by using 65 in common with the two supporting bottles B, C the right hand bottle C of the second stack, which thus becomes bottle A of the third group.

A second stack of the same design as that shown in Figure 2 is then shown attached to the 70 third and similar style stack, using the right hand bottle C of the latter in common with its two supporting bottles B, C to form the new stack.

Where stacks such as that shown in Figure 2 are used they may be further added to by stand- 75

ing an additional bottle F upright on the inverted supported bottle E, as shown in Figure 10.

All of the bottles in the foundation stacks may in like manner be used in common with added bottles as the foundation for further additional stacks, and the upright bottles supported by the foundations may in turn be tied together in groups of three by use of the tie means 2 in the same manner as shown in Figure 1. When so tied they may, in turn, be used for foundations for additional bottles to be superimposed thereupon in like manner to bottles D or E in Figures 1 and 2, so that a great many combinations and designs may be made by use of my invention.

15 Where stacks such as those shown in Figures 1 and 2 are used as separate units in constructing a display, the tie members 1, 2 may be of cylindrical or similar construction, as shown in Figures 7 and 9. Where one of the bottles of the foundation group or stack is used in common with another stack, as shown in Figure 10, if the thickness or diameter of the tie material is appreciable the use of two ties on the same bottle will tend to force one or the other out of its proper plane. 20 Any such difficulty may be eliminated by shaping the loop material of the tie members in semi-cylindrical form in the manner shown in Figures 11, 12, 13, and 14. The first tie used may then be placed with the flat surface of the loop facing 25 upwardly, and when one of the bottles in such stack is used as a common corner bottle for another stack the tie member of the second stack is placed upon such common corner bottle and over the tie already thereon with the flat surface 30 of the loop facing downwardly. Thus the two ties in combination will form the same thickness or diameter as the full portion of the tie intermediate the loops. This use of the split loops is 35 illustrated in Figure 10.

40 It is also desirable in some instances to use a label 3 on the stacks, which may be formed and

secured to the top tie member 2 in the manner shown in Figures 6 and 7.

It is to be noted that in the explanation of my invention for convenience I have used as an illustration the foundation unit or stack of three bottles. Its uses are not limited to the three-bottle stack, as a larger number of bottles may be used in the foundation by providing additional loops in the tying means, and so long as the distance separating the diagonally opposite supporting bottles at their point of contact with the supported bottle is not increased in excess of the outside diameter of the supported bottle at its point of contact with them.

Having thus described my invention, I claim: 15

1. In a means for tying bottles together for stacking purposes, comprising a band of wire or similar material formed into a plurality of outwardly extending loops each substantially defining a semi-circle, said loops being in such spaced relationship that the extended arcs thereof do not overlap. 20

2. In a means for tying bottles together for stacking purposes, comprising a band of wire or similar material formed into a plurality of outwardly extending loops each substantially defining a semi-circle, said loops being in such spaced relationship that the extended arcs thereof do not overlap, and the body of that portion of said band comprised in the loop elements being half 30 the height of the portions intermediate said loop elements. 25

3. In a means for tying bottles together for stacking purposes, comprising a band of wire or similar material formed into a plurality of outwardly extending loops each substantially defining a semi-circle, said loops being in such spaced relationship that the extended arcs thereof do not overlap, and the body of that portion of said band comprised in the loop elements being of 40 semi-cylindrical configuration. 35

ANSON A. MERRICK.
